[57] CLAIM

The ornamental design for a shoe sole, as shown.

DESCRIPTION

FIG. 1 is a right side elevational view of the shoe sole of the present invention;

FIG. 2 is a bottom plan view thereof;

FIG. 3 is a top plan view thereof;

FIG. 4 is a left side elevational view thereof;

FIG. 5 is a front elevational view thereof; and,

FIG. 6 is a rear elevational view thereof.

The broken line showing of a shoe upper is for environmental purposes only and forms no part of the claimed design.
